ABSTRACT: This invention comprises an hydraulic jet stream driller that utilizes a column of drilling mud to supply pressure fluid to three hydraulic drilling jet orifices that are radially spaced from each other within a circle of cutting teeth. The novel tool is preferably clad with galvanized rubber to protect the same from erosion due to the hydraulic and other attrition forces acting on the tool.

HYDRAULIC JET STREAM DRILLER

BACKGROUND OF THE INVENTION

This invention relates to earth boring. More particularly, this invention relates to an improved drilling bit of the type having drilling mud jets.

In the rotary method of earth boring customarily used for drilling oil wells, a fluid referred to herein as drilling mud is pumped downwardly through a tubular drill string to a drill bit which is connected to the lower end of the drill string. The drilling mud passes through the drill bit and circulates back to the surface through an annular space between the well bore or drill pipe and the drill string, as the drilling mud circulates it is filtered to remove the debris and cuttings carried from the bore hole.

SUMMARY OF THE INVENTION

It is an object of this invention to provide a novel fluid-jet-type drill bit.

Another object of this invention is the provision of a novel earth-boring-type drilling bit having, in combination, the combined cutting action of high-pressure hydraulic cutting jets and annular cutting teeth, such as mill teeth.

A further object of this invention is the provision, at the lower end of a drill string, of an earth-boring-type rotary drilling bit having an annular cutting member with at least one eccentrically located high-pressure hydraulic cutting jet within the perimeter defined by the annular cutting member to provide a combination cutting action.

Another object of this invention is the provision of a rotary drilling bit, as set forth in the preceding paragraph, adapted to have drilling mud flow down through the drill string, and angularly dispelled through orifice means formed in an annular wall of the drill bit above the annular cutting member and below other orifice means forming the hydraulic cutting jets, and then recirculating the drilling mud upwardly in the annular space defined by a clearance between the drill string and the inner wall of the drill pipe, for carrying cuttings and debris upwardly therewith.

A still further object of this invention is the provision of a novel fluid-jet-type drill bit having a protective coating or lining of an elastic nonmetallic material, such as vulcanized rubber.

Yet another object of this invention is the provision of a novel rotary drill bit having a protective coating or lining of an elastic nonmetallic material, such as vulcanized rubber.

In summary, the novel hydraulic jet stream driller, and particularly the novel rotary drilling bit embodying the invention is provided with a relatively large central opening and annular ball seat therein permitting the easy penetration and withdrawal of the drill string into the drill pipe and/or bore hole free of extraordinarily high compression on the wall of the bore during entry, and/or the carrying up of mud and slush along with the drill string during withdrawal of the drill string. The mud and slush on the drilling floor forms a dangerous working environment. High compression on the bore wall damages the bore wall and unnecessarily slows the drilling progress. A ball preferably of rubber coated nylon is adapted to be introduced into the drill string for being seated on a ball seat of the novel drilling bit prior to the introduction of the drilling mud. The ball has a density greater than that of the drilling mud, but less than that of water or unity so that the ball will remain seated when the novel drill bit is put into cutting operation. The ball will float up and out of the drill string upon water being introduced into the drill string. Water has a specific gravity of unity or greater. The term drill pipe as used herein is intended to refer to well casing as distinguished from the drill string. The string is free to pulled once the ball has been recovered and water is free to drain from the drill string though the novel drill bit into the bore and well casing.

More particularly, the novel tool, referred to herein as an hydraulic jet stream driller, comprises a section of heavy gauge steel tubing fitted with orifices through which drilling

5 mud is pumped at high velocity. At the bottom of the tool is a sawtoothlike edge defined by mill teeth of hardened steel. As the tool is turned to the right, the mill teeth work in conjunction with the abrasive cutting action of the high velocity jet streams of drilling mud to cut up and loosen material to be circulated out by way of the annular space between the drill string and the well casing.

10 One of the special features of this invention is that the tool is lined with hard rubber that has been bonded to the heavy gauge steel forming the tool. The rubber lining is preferably of one-sixteenth inch thickness and operates to prevent the tool from wearing out so fast due to cavitation, abrasion, erosion, and other forces normally encountered by a rotary drilling tool.

15 The invention further resides in certain novel features of construction, combinations, and arrangements of parts and further objects and advantages of the invention will be apparent to those skilled in the art to which it pertains from the following description of the present preferred embodiment thereof described with reference to the accompanying drawings, which form a part of this specification, wherein the same reference numerals indicate corresponding parts throughout the several views, and in which:

20 FIG. 1 is a cross-sectional view in elevation of a lower end of a tubular drill string having a drilling device attached thereto embodying the invention;

25 FIG. 2 is a cross-sectional view of the drilling device embodying the invention taken along section line 2-2 of FIG. 1;

30 FIG. 3 is a cross-sectional view of the drilling device embodying the invention taken along section line 3-3 of FIG. 1; and

35 FIG. 4 is a cross-sectional view of the drilling device embodying the invention taken along section line 4-4 of FIG. 1.

40 It is to be understood that the invention is not limited to the details of construction and arrangements of parts shown in the drawings and hereinafter described in detail, but is capable of being otherwise embodied and of being practiced and carried out in various ways. It is to be further understood that the terminology employed herein is for the purpose of description and there is no intention to herein limit the invention beyond the requirements of the prior art.

45 Referring to FIGS. 1, 2, 3, and 4, the reference numeral 10 indicates generally a fluid jet cutting device embodying the invention. The device 10 is affixed, preferably by welding by a circular bead 11, to a lower end of a tubular drill string 12 within a well casing or drill pipe 13. The well casing 13 has an inner wall that defines a well bore 14 for purposes of describing and claiming the apparatus of this invention.

50 More particularly, the device 10 comprises a tubular body 15 having a cylindrical body portion 16 and a frustoconical gooseneck portion 17 welded by the bead 11 at a circular upper end thereof to a circular lower end 19 of the tubular drill string 12. The height of the gooseneck portion 17 is about the same as the height of the cylindrical body portion 16 down to an horizontal partition 20. Below the partition 20 is a skirt portion 21 integrally connected to and depending from the cylindrical body portion 16.

55 60 The dependent skirt portion 21 is counterbored to have a greater internal diameter than the internal diameter of the cylindrical body portion 16. The outer diameters of each of the portions 16 and 21 are preferably the same. At a lower circular end face 22 of the depending skirt portion 21 is affixed, preferably by a circular weld bead 23, a set of circularly arranged mill teeth 24. The mill teeth 24 are shown in FIGS. 1 and 2, and define a circular mill cutter, indicated generally by the reference numeral 25.

65 70 The partition 20 is preferably located at the lower end of the cylindrical body portion 16. The skirt portion 21 is of about the same height as the cylindrical body portion 16.

75 Fluid such as liquids including water and drilling mud are channeled down the tubular drill string 12 into the device 10, and more particularly into the gooseneck portion 17 and the cylindrical body portion 16, through a central bypass

passageway 30, and/or a plurality of fluid jet orifices 31, 32, and 33, centrally formed in three hexagonal head stud bolts 34, 35, and 36, respectively. The stud bolts 34, 35, and 36 are threaded into the partition 20 and are equiangularly spaced from each other in increments of 120°. Moreover, as seen in FIGS. 2 and 3, the passageway 30 is cylindrically shaped and centrally located. The nozzles 31, 32, and 33 are each cylindrically shaped, but are eccentrically located relative to the central passageway 30. The nozzles 31, 32, and 33 are each located at a different radial distance from the central passageway 30 for defining three discrete cutting paths when the device 10 is in operation. Preferably, the nozzle 31 is spaced radially inwardly from the nozzle 33 by the same distance that the nozzle 32 is spaced radially outwardly from the nozzle 33.

Fluid from the fluid jet orifices 31, 32, and 33 accumulates within the skirt portion 21 during the cutting operation. During the cutting operation the entire device 10 is being rotated via the drill string 12 in a counterclockwise direction as seen in FIGS. 2 and 3, and in a clockwise direction as seen in FIG. 4. Thus the circular mill cutting 25 is put into effective use. The fluid jet orifices 31, 32, and 33 will not be effective as cutting means, however, unless a rubber coated nylon ball 40, having a density greater than that of the drilling fluid or mud and less than that of water or unity, is seated on a ball seat 41. The ball seat 41 is cylindrically shaped and is press fitted into a counterbore 42 of the passageway 30.

The passageway 30 is centrally formed in a tubular ball seat portion 44 of the partition 20. The ball seat portion 44 extends above an annular planar portion 45 of the partition 20 into which the stud bolts 34, 35, and 36 are threaded. The upper end of the ball seat portion 44 is countersunk to form a funnel-shaped or outwardly flared upper end portion 46 of the passageway 30. The portion 46 serves as a guide for the ball 40 onto its seat 42. The ball seat 42 has a sharp circular inner edge 47 that provides line contact with the rubber coating of the ball 40 for effectively partitioning and thereby isolating the passageway 30 from the upper side of the partition 20 and prevents the transgression of fluid therest.

The buildup of fluid, cuttings, and other debris beneath the partition 20 is released through preferably four cylindrical peripheral ports 51, 52, 53, and 54 formed in the skirt 21, FIGS. 1 and 3.

In order to obtain the maximum benefit of the fluid buildup within the cylindrical inner chamber defined by the skirt 21, as seen in FIGS. 1 and 3, the four ports 51, 52, 53, and 54 are drilled at a tangent to a circle concentric within the skirt 21, but having a diameter less than that of the skirt 21 and greater than the diameter of the ball 40, and therefore may be described as having been drilled along a chord of a circle. The ports 51, 52, 53, and 54 are not radial and are not tangential to the skirt 21. The ports 51, 52, 53, and 54 are located in a plane about one-third of the distance from the partition 20 to the cutting edges of the mill teeth 25. Once the spent fluid, cuttings, and other debris exit the ports 51, 52, 53, and 54, the fluid is forced upwardly through an annular space between the outer surface of the device 10 and the well bore 14, and then subsequently between the drill string 12 and the well bore 14, to the surface where the fluid is preferably filtered, and recirculated down through the drill string 12 and into the device 10.

A novel feature of this invention is the provision of the non-metallic elastic lining or coating of the exterior 60 of the device 10 and the walls or surfaces 62 and 63 of the chamber within the skirt 21 of the device 10. The lining is preferably of a vulcanized hard rubber bonded to the heavy gauge steel body 15 and is indicated generally by the reference numeral 70. Preferably, the ports 51, 52, 53, and 54 are also lined with vulcanized rubber. The object of the rubber lining 70 is to protect the portions of the device 10 that are exposed to the highly turbulent and erosive hydraulic cutting action of the fluid jetting through the nozzles 31, 32, and 33, as well as the abrasive action of the cuttings and other debris. The rubber

lining 70 is considered to extend the useful life of the device or tool 10. It will be noted in FIG. 1, that the rubber lining 70 also covers the weld bead 23 and the sides of the mill teeth 25.

It will be understood that this invention can be modified to adapt it to various circumstances and conditions, and it is accordingly desired to comprehend within the purview of this invention such modifications as may be considered to fall within the scope of the appended claims.

I claim:

1. In an apparatus adapted to be lowered in a well bore on a tubular string, fluid jet cutting means having drill bit means comprising circular mill cutter means adapted to rotate about a central axis for performing a cutting action in a bottom of a well bore, fluid jet passage means comprising horizontal partition means with orifice means formed therein eccentrically of said central axis and adapted to direct jet streams of drilling fluid in a downward direction parallel to said central axis, relatively large closable central cylindrical opening means coaxial with said central axis in said partition means for permitting fluid to pass therethrough when introducing and removing said jet cutting means from the well bore, tubular skirt means depending from said partition means and having said circular mill cutter means connected thereto at a downwardly facing edge thereof, means forming relatively large openings in said tubular skirt means for directing fluid horizontally outwardly thereof at a 45° included angle with a diameter of said skirt means against the wall of the well bore in such a manner that the fluid is permitted to flow downwardly in the tubular string and through said orifice means and into said tubular skirt means and against a bottom of the well bore and through said relatively large opening means against the wall of the well bore for carrying cuttings and other debris upwardly between the tubular string and the well bore, a rubber-coated nylon ball having density less than that of water and greater than that of drilling mud, and a seat for said ball formed in the upper end of said cylindrical opening means for seating said ball thereon and closing said central cylindrical opening means when drilling mud has been introduced into the tubular string and for opening the same by introducing water into the tubular string and floating said ball off said seat and recovering said ball at the upper end of the tubular string.
2. In an apparatus as set forth in claim 1, wherein said orifice means formed in said partition means comprise three orifices equiangularly displaced each other and radially spaced from each other in such a manner as to define three discrete cutting paths.
3. In an apparatus as set forth in claim 1, elastic nonmetallic means bonded to and lining said tubular skirt means and a lower side of said partition means.
4. In an apparatus as set forth in claim 3, wherein said elastic nonmetallic means is vulcanized rubber.
5. In an apparatus adapted to be lowered in a well bore on a tubular string, fluid jet cutting means having drill bit means comprising circular mill cutter means adapted to rotate about a central axis for performing a cutting action in a bottom of the well bore, fluid jet passage means comprising transverse partition means with orifice means formed therein eccentrically of said central axis and adapted to direct jet streams of drilling fluid in a downward direction parallel to said central axis, relatively large closable central cylindrical opening means coaxial with said central axis formed in said partition means for permitting fluid to pass therethrough when introducing and removing said jet cutting means from the well bore, tubular skirt means depending from said partition means and having said circular mill cutter means connected thereto at a downwardly facing edge thereof, means forming relatively large openings in said tubular skirt for directing fluid outwardly thereof against the wall of the well bore in such a manner that the fluid is permitted to flow downwardly in the tubular string and through said orifice means and into said tubular skirt means and against a bottom of the well bore and through said relatively large opening means against the wall of the well bore for carrying cuttings and other debris upwardly

between the tubular string and the well bore, a ball having a density of less than that of water and greater than that of drilling mud, and a seat for said ball formed in the upper end of said central cylindrical opening means for seating said ball thereon and closing said central cylindrical opening means when drilling mud has been introduced into the tubular string and for opening the same by introducing water into the tubular string and floating said ball off said ball seat and recovering the same at the upper end of the tubular string.

6. In an apparatus as set forth in claim 5, wherein said orifice means formed in said partition means define a plurality of discrete cutting paths.

7. In an apparatus as set forth in claim 5, elastic nonmetallic means lining said tubular skirt means and a lower side of said partition means.

8. In an apparatus adapted to be lowered in a well bore on a tubular string, fluid jet cutting means having drill bit means comprising cutter means adapted to rotate about a central axis for performing a cutting action in a bottom of the well bore, fluid jet passage means comprising partition means with orifice means formed therein eccentrically of said central axis and adapted to direct at least one jet stream of drilling fluid in a downward direction, relatively large closable central cylindrical opening means coaxial with said central axis formed in said partition means for permitting fluid to pass therethrough when introducing and removing said jet cutting means from the well bore, tubular skirt means depending from said partition means and having said cutter means connected thereto, means forming relatively large openings in said tubular skirt for directing fluid outwardly thereof against the wall of the well bore in such a manner that the fluid is permitted to flow downwardly in the tubular string and through said orifice means and into said tubular skirt means and against a bottom of the well bore and through said relatively large opening means against the wall of the well bore for carrying cuttings and other debris upwardly between the tubular string and the well bore, a ball having a density of less than unity and greater than that of the drilling fluid, and a seat for said ball formed in the upper end of said central cylindrical opening means for seating said ball thereon and closing said central cylindrical opening means when a fluid of a density less than the density of said ball has been introduced into the tubular string and for opening the same by introducing fluid of a density greater than the density of said ball into the tubular string and floating said ball off said ball seat and recovering the ball at the upper end of the tubular string.

9. In an apparatus as set forth in claim 8, wherein said cutter means comprise a circle of mill cutter teeth affixed to a downwardly facing edge of said tubular skirt means.

10. In an apparatus as set forth in claim 8, elastic nonmetallic means lining said tubular skirt means.

11. In an apparatus adapted to be lowered on a tubular string into a well bore, a fluid jetting device including a drill bit having cutting means thereon and jetting nozzle means for performing cutting action in a well bore, said device having a fluid passage adapted to receive fluid from the tubular string and including generally radial port means above said drill bit

cutting means and below said jetting nozzle means for directing fluid from said port means against a wall of the well bore, and said jetting nozzle means adapted to direct cutting fluid in a downward direction in the well bore.

5 12. In an apparatus as set forth in claim 11, wherein said port means direct the fluid at an horizontal vector angle that includes an horizontal radial vector and an horizontal tangential vector of the well bore.

13. In an apparatus as set forth in claim 11, wherein said port means direct the fluid horizontally outwardly of said fluid jetting device at an acute angle with a diameter of the well bore.

14. In an apparatus as set forth in claim 11, wherein said jetting nozzle means comprise a plurality of axially directed orifices angularly displaced from each other.

15. In an apparatus as set forth in claim 11, wherein said jetting axially directed nozzle means comprise a plurality of nozzles radially spaced from each other in such a manner as to define three discrete cuttings paths as said fluid jetting device is rotated.

20 16. In an apparatus as set forth in claim 11, wherein said drill bit comprises circularly arranged mill teeth.

17. A drill bit for attachment to a lower end of a tubular drill string through which drilling mud is pumped downwardly to the bit for cleaning a well bore, the drill bit comprising, in combination, a drill bit having a body, at least one fluid jet nozzle through said body for directing a jet of drilling mud from the body, a fluid bypass passageway through said body for passing drilling mud through said body, a valve seat in said bypass passageway adapted to have a valve member seat thereon and block the downward passage of drilling mud through said bypass passageway, and port means formed in said body below said fluid jet nozzle for directing the drilling mud laterally outwardly of said body at an acute angle with a diameter of the well bore.

35 18. A drill bit as set forth in claim 17, further comprising, in combination, circularly arranged mill teeth affixed to a lower end of said body below said port means.

19. A drill bit as set forth in claim 17, further comprising, in combination, elastic nonmetallic means lining said body at the lower end thereof to protect the same from the hydraulic cutting action of the drill bit.

20 20. In an apparatus adapted to be lowered on a tubular string into a well bore, a fluid jetting device including a drill bit having cutting means thereon and jetting nozzle means for performing cutting action in a well bore, and elastic nonmetallic means lining said fluid jetting device at the lower end thereof to protect the same from the hydraulic cutting action of the drill bit.

50 21. A drill bit attachment to a lower end of a tubular drill string through which drilling mud is pumped downwardly to the bit for cleaning a well bore, the drill bit comprising, in combination, a drill bit having a body, at least one fluid jet nozzle through said body for directing a jet of drilling mud from the body, and elastic nonmetallic means lining said body at the lower end thereof to protect the same from the hydraulic cutting action of the drill bit.
